UNITED STATES PATENT OFFICE.

JOSEPH WOLFF, OF BROOKLYN, NEW YORK, ASSIGNOR TO SONORA, INC., A CORPORATION OF NEW YORK.

DESIGN FOR A PHONOGRAPH CABINET.

Application filed January 10, 1922. Serial No. 151. Term of patent 7 years.

To all whom it may concern:

Be it known that I, JOSEPH WOLFF, a citizen of the United States of America, residing in the borough of Brooklyn, county of Kings, city and State of New York, have invented a new, original, and ornamental Design for Phonograph Cabinets, of which the following is a specification, reference being had to the accompanying drawing, forming a part thereof.

This figure is a perspective view of a phonograph cabinet illustrating my improved design.

I claim:

The ornamental design for a phonograph cabinet, substantially as shown.

This specification signed and witnessed this 23rd day of December, 1921.

JOSEPH WOLFF.

Witnesses:

A. M. SWEENEY,
M. E. CARPENTER.
